APPARATUS FOR SEPARATING LIQUIDS OF
DIFFERENT GRAVITYWilhelm Linnmann, Jr., Essen-Altenessen,
GermanyApplication February 24, 1930, Serial No. 430,644
In Germany June 20, 1928

4 Claims. (Cl. 210—56)

My invention relates to improvements in apparatus for separating liquids of different specific gravity, such for instance as water mixed with benzol and/or benzene, gasoline, oil and the like and more particularly in apparatus, comprising a receptacle in which the liquids are separated by difference in specific gravity. An object of the improvements is to provide an apparatus in which the liquids are rapidly separated, 10 and with this object in view my invention consists in supplying the liquids to the receptacle in tangential direction so that separation is supported by centrifugal action. A further object is to so construct the receptacle and the inlet passage thereto and the outlet therefrom that a particular mass of the liquids to be separated will be caused to move over a path as long as possible within the receptacle so as to remain within the receptacle a sufficient length of time to assure 20 separation by the natural tendency of the liquids to separate, aided to some extent by centrifugal force.

A further object is to provide such a device in which the liquid is caused to enter the receptacle in such a way as to cause a minimum of disturbance of the liquid in the receptacle.

A further object is to provide such a device in which the discharge passage begins at a point near the bottom of the receptacle so as to allow 30 the discharge only of the heavier liquid or liquids, the discharge passage being, however, carried to a higher point so as to cause the liquids in the receptacle to rise to such point so as to insure that the lighter liquids will always remain in 35 the upper part of the receptacle and therefore can not escape from said receptacle.

A further object is the provision in such a device wherein the liquids are caused to rotate within the receptacle of a discharge passage located near the bottom of said receptacle and at the outer edge thereof, so as to allow the discharge only of the heavier liquids which drop to the bottom due to their greater specific gravity and which are driven to the outer edge due to 45 the action of centrifugal force on liquids of different specific gravity.

Other objects will be apparent from the description and drawing.

For the purpose of explaining the invention 50 two alternative embodiments of the same have been shown in the accompanying drawing, in which the same letters of reference have been used in all the views to indicate corresponding parts. In said drawing

Fig. 1 is a sectional elevation of the apparatus taken on the line 1—1 of Fig. 2.

Fig. 2 is a sectional plan view taken on the line 2—2 of Fig. 1, and

Fig. 3 is a similar sectional plan view showing 60 a modification.

The present invention is an improvement on the devices shown, for example, in the patents to Linnmann 1,671,115 granted May 29, 1928 and 1,655,191 granted January 3, 1928.

The purpose of the device embodying the present invention, as in the case of my said earlier patents, is to provide a receptacle having an inlet for liquids of different specific gravity and an outlet therefrom for the liquid or liquids of higher 70 specific gravity. The lighter liquids such as gasoline and oil remain in the receptacle and must be removed therefrom from time to time by the attendant. Such devices find application in garages, repair shops, and factories and other 75 places, to prevent gasoline, oil, etc. from flowing into the sewers and thereby prevent a well-known cause of sewer explosions.

In the construction shown in my earlier patents, means, such as a float, are devised to automatically close the outlet after a certain amount of the lighter liquid has accumulated in the receptacle. While such automatic means may also be applied to the device disclosed herein, it is to be understood that the present invention is 85 not limited to use with such devices, as it will be fully capable of performing the function for which it is intended if the attendant will remove the lighter liquids at proper intervals.

In the illustrative embodiment of the invention 90 shown in Figs. 1 and 2, the separating apparatus comprises a vertical cylindrical casing, *b*, the upper end of which may be open for convenience in cleaning, but said opening is preferably and usually closed by any suitable means such as lid, *g'*. The discharge pipe, *e*, as shown, is connected 95 to the side of the casing near its bottom, and is formed with a vertical portion, *e'*, which extends upwardly to a point above the middle of the receptacle, *b*, at which point it is shown as having 100 a more or less horizontal continuation, *e''*. The letter *a* designates the intake pipe for the plurality of liquids to be separated. Said intake pipe is preferably as shown, so located that the intake port is below the section *e''* of the discharge pipe. 105 It will be readily seen that the level of the liquid in the receptacle, *b*, will be at approximately the plane indicated by the letter *f*, so that the entry port to the receptacle is submerged. As most of the lighter liquids will have risen to the top, 110

they will be located above the entry port, so that the entering liquid will have a minimum effect upon the separated lighter liquids. The possibility of disturbing the separated lighter liquids and recomingling them with the heavier liquids is further obviated by the peculiar construction of the entry port. As shown, the intake pipe, *a*, opens into the receptacle, *b*, in tangential direction, and preferably into the circumferential enlarged portion, or gutter, *c*, of the receptacle, which enlarged portion may be in the form of a collar cast integral with the receptacle wall intermediate of its ends. The said gutter is preferably gradually reduced in cross-sectional area from the intake towards the end remote therefrom. As shown, this gutter throughout its length opens at its inner side in a generally horizontal plane into the receptacle. It will be noted that the said gutter, *c*, is located below the normal liquid level, so that the entry port is submerged. As the cross-sectional area of the gutter is progressively decreasing, and as liquids are practically incompressible, it will be noted that the liquids will be gradually forced out of the gutter as the movement progresses. Therefore, instead of having the liquid enter the receptacle in a concentrated stream at high velocity, it enters the receptacle and mingles with the liquid therein at a relatively low velocity, due to the larger effective area of the entrance port. This relatively low velocity of entrance will impose the minimum opposition to the rise of the lighter components and the sinking of the heavier components. Furthermore, the entry angle of the entering liquids is somewhat between a radial line and the tangent so that the entering liquid has the effect of causing rotation of the body of liquid within the receptacle, which rotation is effected with a minimum amount of agitation and recomingling of the liquids originally standing in the receptacle. In view of this rotation of the mass of liquid in the receptacle, a particular quantity of liquid entering the receptacle is caused to travel through a very long path before it can possibly reach the exit port. It necessarily requires considerable time to follow this long path (sometimes many times around the axis of the receptacle) during which time further separation occurs, i. e. any liquids which have not been separated by the centrifugal action in the gutter, *c*, will have adequate time to separate so that the lighter liquids may rise to the top and the heavier liquids will drop to the bottom where they may pass out through the discharge pipe, *e*, *e'*, *e''*. Practical experiments have shown that this rotary motion occurs much more strongly at the lower part of the receptacle than at the upper.

The modification shown in Fig. 3 is similar to the one illustrated in Figs. 1 and 2, but in lieu of the cylindrical receptacle a receptacle, *b'*, of generally square cross-section is used, and the enlarged portion or gutter, *c'*, is shaped accordingly.

I claim:

1. Apparatus for separating liquids of different specific gravities comprising a receptacle

having a tangential inlet for the liquids intermediate of its ends and a gutter extending therefrom circumferentially of the receptacle wall in which the liquids of different specific gravities are separated by centrifugal force, said gutter being disposed in a plane substantially at right angles to the receptacle and terminating in circumferentially spaced relation from the liquid inlet, said gutter throughout its length having upper and lower surfaces disposed substantially at right angles to the receptacle wall and defining an open inner side of the gutter through which the liquid of lower specific gravity is delivered in a concentrated stream into the receptacle to facilitate rising thereof into the upper part of the receptacle.

2. An apparatus for separating liquids of different specific gravities comprising a storage receptacle, a discharge passage leading from near the bottom of said receptacle and constructed to maintain a liquid level therein at a substantial distance above the bottom thereof and an inlet passage for the entrance of a plurality of liquids to be separated, located at a point a substantial distance above said discharge passage and a substantial distance below the lower liquid level of the lighter liquid, said inlet passage being disposed generally tangentially of said receptacle, and a gutter forming a continuation of said inlet passage extending circumferentially of the receptacle wall.

3. An apparatus for separating liquids of different specific gravities comprising a storage receptacle, a discharge passage leading from near the bottom of said receptacle and constructed to maintain a liquid level therein at a substantial distance above the bottom thereof and an inlet passage for the entrance of a plurality of liquids to be separated, located at a point a substantial distance above said discharge passage and a substantial distance below the lower liquid level of the lighter liquid, said inlet passage being disposed generally tangentially of said receptacle, and a gutter forming a continuation of said inlet passage extending circumferentially of the receptacle wall with its open side facing toward the axis of the receptacle.

4. An apparatus for separating liquids of different specific gravities comprising a storage receptacle, a discharge passage leading from near the bottom of said receptacle and constructed to maintain a liquid level therein at a substantial distance above the bottom thereof and an inlet passage for the entrance of a plurality of liquids to be separated, located at a point a substantial distance above the discharge passage and a substantial distance below the lower liquid level of the lighter liquid, said inlet passage being disposed generally tangentially of said receptacle, and a gutter forming a continuation of said inlet passage extending circumferentially of the receptacle wall, said gutter being formed of gradually decreasing cross-sectional area.

WILHELM LINNMANN, JUN. 140
